ARBOR FOR AND METHOD OF FORMING A
CORED MOLD

Finley F. Ellingwood, Plainfield, and Stephen A. Mraz, Perth Amboy, N. J., assignors, by mesne assignments, to Union Carbide and Carbon Corporation, New York, N. Y., a corporation of New York

Application December 9, 1938, Serial No. 244,726

4 Claims. (Cl. 22—136)

This invention relates to the molding of articles from casting resins and similar plastic materials in molds formed by slush casting, i. e., by dipping arbors into a congealable material, preferably molten lead, type metal, and the like.

The preparation of articles from casting resins and similar plastic materials requires the making of molds by chilling and hardening a low melting point substance, such as lead, or a similarly 10 congealable material around an arbor or die, removing the mold or shell so formed, pouring a viscous resin into the mold and hardening the cast resin by placing the mold and its contents into a temperature controlled oven. This process is satisfactory for casting solid forms as knife 15 handles, pipe stems, rods, and the like where a core is not required; but in attempting to obtain hollow cast resins in this manner by preparing slush-cast molds with integral cores it has been found that air is frequently entrapped in the bore of the arbor for forming the core and prevents the lead from rising to the same height each time a slush mold is made. In certain cast articles, however, it is desirable to have openings 20 or bores extending a fixed and/or a predetermined length into the casting, as for example, in castings for knife handles, utensil handles, forks, pencil barrels, and the like.

It is the object of this invention to provide integrally cast cores forming openings of definite 25 and predetermined length in resinous cast articles and to produce hollow articles which require no further machining after being removed from the casting mold. Briefly, the present invention provides an improved arbor having a bore extending in a longitudinal or axial direction partially therethrough and connected by a lateral vent extending in a lateral or radial direction to the outside longitudinal surface of the arbor which enables the arbor when submerged 30 in a bath of molten metal to discharge entrapped air from the bore and allow the molten metal to flow into and fill the opening. The metal slug filling the vent unites the core with the mold wall formed over the outer surface of the arbor; but the subsequent withdrawal of the arbor 35 serves to shear away the lead slug from both the core and the mold wall.

The foregoing object, as well as other and additional objects, will be more readily understood by referring to the following description and the drawing which illustrates an embodiment of the invention.

In the drawing:

55 Figure 1 is a lateral view of an arbor, showing

a lead shell or casting mold deposited on the arbor, a portion of the lead shell being cut away to show the structure of the arbor more clearly;

Figure 2 is a vertical sectional view of the arbor showing the internal structure of the slush 5 molded lead shell more clearly;

Figure 3 is a vertical section of the apparatus shown in Fig. 1 with the arbor almost withdrawn and the lead slug dropping out of the air vent; 10

Figure 4 is a perspective view of a finished hardened cast resin body removed from the lead casting shell and provided with an opening of definite predetermined length and shape. 15

Referring now in more detail to the drawing, an arbor Fig. 1 comprises a handle 11, an insulating sheath 12 and a backing plate 10 which has mounted on its lower surface a molding member 13; screw bolts 19 secure the member to the plate. The section of the arbor in Fig. 2 shows the axially or longitudinally disposed bore 15 running to any predetermined depth into the molding member 13. At the end of the bore a vent 16 is provided in the side of the molding 20 member 13 and is tapered to broaden outwardly. The vent as shown is laterally directed, i. e. extends in a radial direction through the member from the end of the bore 16 to open at the outer longitudinal surface of the member and thereby 25 forming cutting edges at the bore terminal and the exterior surface; the vent need only be large enough to insure escape of gas.

When dipped into molten lead, a lead shell or casting form 14 freezes and hardens conformably 30 over the molding member 13 and the portion of the backing plate dipped therein. The arbor is then withdrawn from the lead bath and the lead shell further cooled. When sufficiently hardened, the lead skin layer or shell is jarred loose from 40 the arbor; and the arbor is then withdrawn, leaving a relatively clean and sharply formed lead casting shell or mold.

The lead shell 14 that is formed on the arbor has an internally disposed core 20 (shown in 45 section in Figs. 2 and 3) formed integrally therewith; the core 20 is formed when the molten lead, or similar congealable material, runs up into the bore 15 of the member 13 and displaces the entrapped air which escapes by being forced 50 out through the vent 16. Upon further submersion of the arbor a lead slug 17 forms in the vent 16 and bridges across the core 20 and the outer shell 14. The length of the core 20 55

is determined by the position of the air vent 16 for the bore 15.

The removal of the casting shell 14 from the arbor is effected by jarring or knocking it loose; 5 this simultaneously shears or cuts the slug 17 free from the core 20 and the side wall 14, and upon further withdrawal of the arbor the slug 17 drops out of the air vent 16 as shown in Fig. 3, leaving the arbor ready for another slush 10 molding step.

The lead shell is then ready for the casting step, in which process the cavity 21 is filled with liquid resin; then the lead shell and its viscous resin contents are stoved, being heated at such 15 a temperature and for such a period of time that the resin sets or cures to a permanently hardened state to form a body such as that shown at 22, Fig. 4, with a central opening 23 extending part of the way up into the body.

20 The venting of an arbor as disclosed herein permits the making of complicated molds with cores of any definite length or shape; such cores conform perfectly to the bore of the arbor without the formation of protuberances as heretofore, 25 which protuberances, moreover, frequently necessitated clipping in order to provide a smooth molding surface for the casting resin. The process and apparatus of this invention enable an operator to make cast resin articles having 30 cores of a definite and predetermined length with equal if not greater ease than was possible with the processes heretofore used and which invariably resulted in cores of non-uniform length.

It is to be understood that the invention may 35 be variously otherwise embodied and that the disclosure herein specifically described is merely illustrative and not limitative of the invention except as defined in the claims.

What is claimed is:

40 1. The method of forming a cored mold by slush-casting which comprises dipping into a bath of molten metal an arbor having a longitudinal casting surface, a bore extending longitudinally and partially through the arbor and a laterally directed vent in the arbor connecting 45 the bore with the longitudinal surface of the arbor whereby the molten metal coursing through the bore rises therein and into the vent to dis-

charge gases therefrom, said metal freezing on the surface of the arbor and in the bore thereof, removing the arbor with the adhering metal from the bath, and withdrawing the arbor from the mold with its integrally formed core formed by the metal adhering to the arbor, said arbor simultaneously cutting and removing the metal slug filling the vent from the mold by its withdrawal. 5

2. The method of forming a cored mold by slush casting which comprises dipping into a bath 10 of molten metal an arbor having a longitudinal casting surface, a bore extending longitudinally and partially through the arbor and a laterally directed vent in the arbor tapered to broaden outwardly from the bore and connecting the bore 15 with the longitudinal surface of the arbor whereby the molten metal coursing through the bore rises therein and into the vent to discharge gases therefrom, said metal freezing on the surface of the arbor and in the bore thereof, removing the 20 arbor with the adhering metal from the bath, and withdrawing the arbor from the mold with its integrally formed core formed by the metal adhering to the arbor, said arbor simultaneously cutting and removing the metal slug filling the 25 vent from the mold by its withdrawal.

3. An arbor for forming a hollow shell casting mold with an integrally formed core extending into the casting space, the arbor having a longitudinal casting surface, a bore extending longitudinally and partially through the arbor and corresponding to the core of the mold to be formed, and a laterally directed vent connecting the bore with the longitudinal surface of the arbor. 30

4. An arbor for forming a hollow shell casting mold with an integrally formed core extending into the casting space, the arbor having a longitudinal casting surface, a bore extending longitudinally and partially through the arbor and corresponding to the core of the mold to be formed and a laterally directed vent tapered to broaden outwardly from the bore and connecting the bore with the longitudinal surface of the arbor and determining the height of the core. 40
